(57) CLAIM

I claim the ornamental design for a clothes hanger, as shown and described.

DESCRIPTION

FIG. 1 is a perspective view of a clothes hanger, showing the new design;

FIG. 2 is a front elevational view thereof, the rear elevational view being a mirror image thereof;

FIG. 3 is a top plan view thereof;

FIG. 4 is a bottom plan view thereof;

FIG. 5 is a left-side elevational view thereof; and,

FIG. 6 is a right-side elevational view thereof.
